(57) **CLAIM**

The ornamental design for a gaming machine, as shown and described.

DESCRIPTION

FIG. 1 is a perspective view from above and to the right of a gaming machine showing the new design.

FIG. 2 is a left side view of the gaming machine shown in FIG. 1.

FIG. 3 is a right side view of the gaming machine shown in FIG. 1.

FIG. 4 is a front view of the gaming machine shown in FIG. 1.

FIG. 5 is a rear view of the gaming machine shown in FIG. 1.

FIG. 6 is a top view of the gaming machine shown in FIG. 1; and,

FIG. 7 is a bottom view of the gaming machine shown in FIG. 1.

The broken line showing of portions of the gaming machine depicts the boundary of the claimed design and forms no part thereof.

1 Claim, 7 Drawing Sheets
